US00D764835S

(12) **United States Design Patent** (10) Patent No.: **US D764,835 S**
(45) Date of Patent: **** Aug. 30, 2016**

(54) **COVERING FOR AN ARCHITECTURAL OPENING**

(71) Applicant: **Hunter Douglas Inc.**, Pearl River, NY (US)

(72) Inventors: **Nickolas C. Buccola, Jr.**, Brighton, CO (US); **Terrence M. Drew**, Superior, CO (US); **Kenneth M. Faller**, Thornton, CO (US); **Kent A. Smith**, Broomfield, CO (US)

(73) Assignee: **Hunter Douglas Inc.**, Pearl River, NY (US)

(**) Term: **14 Years**

(21) Appl. No.: **29/497,575**

(22) Filed: **Jul. 25, 2014**

Related U.S. Application Data

(63) Continuation of application No. 14/212,387, filed on Mar. 14, 2014.

(60) Provisional application No. 61/801,811, filed on Mar. 15, 2013, provisional application No. 61/834,080, filed on Jun. 12, 2013.

(57) **CLAIM**

We claim the ornamental design for a covering for an architectural opening, as shown and described.

DESCRIPTION

FIG. 1 is an isometric view of a covering for an architectural opening in accordance with the claimed design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The dash-dot-dash broken lines illustrate the boundaries of the claimed design and form no part thereof.

1 Claim, 5 Drawing Sheets
